(57) **CLAIM**

The ornamental design for the sensor device for control of fluid distribution in a watering system, as shown and described.

DESCRIPTION

FIG. 1 is a perspective view of a sensor device for control of fluid distribution in a watering system in accordance with an embodiment of the present invention;

FIG. 2 is a front view of the sensor device for control of fluid distribution in a watering system of FIG. 1;

FIG. 3 is a back view of the sensor device for control of fluid distribution in a watering system of FIG. 1;

FIG. 4 is a left side view of the sensor device for control of fluid distribution in a watering system of FIG. 1;

FIG. 5 is a right side view of the sensor device for control of fluid distribution in a watering system of FIG. 1;

FIG. 6 is a top view of the sensor device for control of fluid distribution in a watering system of FIG. 1; and,

FIG. 7 is a bottom view of the sensor device for control of fluid distribution in a watering system of FIG. 1.

The broken lines of FIGS. 1-7 are illustrative of the visible environmental structure of the sensor device for control of fluid distribution in a watering system and form no part of the claimed design.

1 Claim, 6 Drawing Sheets
